UNITED STATES PATENT OFFICE.

GEORGE N. POLALES, OF CHICAGO, ILLINOIS, ASSIGNOR OF ONE-HALF TO ABE ROSSET,
OF CHICAGO, ILLINOIS.

DESIGN FOR A MOTOR-METER CASING.

60,260.

Specification for Design.

Patented Jan. 17, 1922.

Application filed June 2, 1921. Serial No. 474,569. Term of patent 14 years.

To all whom it may concern:

Be it known that I, GEORGE N. POLALES, a citizen of the United States, and a resident of the city of Chicago, in the county of Cook and State of Illinois, have invented a new, original, and ornamental Design for a Motor-Meter Casing, of which the following is the specification, reference being had to the accompanying drawings, forming a part thereof.

In the drawings:

Figure 1 is a front elevation of a design

for a motor-meter casing embodying my invention.

Figure 2 is a top plan view thereof.

Figure 3 is a side elevation.

I claim:

The ornamental design for a motor-meter casing.

GEORGE N. POLALES.
